M. R. CLEMENTS

SAVINGS BANK

Filed July 16, 1923

Fig. 3.

Fig. 4.

Patented May 19, 1925.

UNITED STATES PATENT OFFICE.

MENESEE R. CLEMENTS, OF SOUTH BEND, INDIANA.

SAVINGS BANK.

Application filed July 16, 1923. Serial No. 651,992.

To all whom it may concern:

Be it known that I, MENESEE R. CLEMENTS, a citizen of the United States, residing at South Bend, in the county of St. Joseph and State of Indiana, have invented a certain new and useful Improvement in Savings Banks, of which the following is a full, clear, concise, and exact description, reference being had to the accompanying drawings, forming a part of this specification.

My invention relates to savings-banks and is concerned with a device which I term a "coin actuated clock bank." The underlying idea is the provision of a twenty-four hour clock movement which is kept running from day to day by the regular deposit of coins, mechanism being provided so that insertion of a coin is necessary before winding of clock can be accomplished.

The proposal of my invention is to encourage the habit of regular and systematic saving, and with this in view I utilize the idea of the clock movement which must be wound from day to day and is provided a positive mechanical connection between the clock and entry way to a coin deposit compartment, the arrangement being such that the clock can be wound only by the insertion of a coin of the proper denomination. In this way, in order to keep the clock running, it is necessary for one to deposit a coin of the proper denomination regularly, and not only do I provide a useful time-piece, operated in this novel way, but I also provide means for constantly reminding the owner of such a bank whether or not he has made his daily deposit.

It is well known that banking institutions frequently adopt the system of encouraging savings by providing their depositors with banks and small portable devices, for the purpose of depositing coins at various intervals, the banking institution holding the key.

I provide my bank with a lock and key in order that it may effectually play a part in this system of thrift.

A further object of my invention is to provide a device of the character described above which will be of simple construction, attractive in design, and capable of economical manufacture.

In the accompanying drawings forming a part of this specification and in which like

numerals are employed to designate like parts throughout same—

Fig. 1 is a side elevational view of my coin actuated clock bank, a portion of the casing broken away, so as to clearly reveal the structure.

Fig. 2 is a plan view looking down on top of my coin actuated clock bank, a portion of the casing broken away so as to clearly reveal the structure.

Fig. 3 is a front elevational view of the coin actuated clock bank of my invention, showing the dial of the clock movement, and

Fig. 4 is a front elevational view of the wall 16 containing coin tripping aperture 8 and coin slot 9, also clock setting stem 70 aperture 15.

The housing of the device comprises a sheet metal case 14, which is conveniently formed from a metal stamping. A floor on lower portion 24 is secured to upper portion 75 in any suitable manner, preferably in such a way as to make it difficult to open the bank without actually having a key to the lock thereto. A swinging portion 25 is provided; this portion being hinged in a suitable manner at 26, upon portion 25, a lock 13 is secured thereto, for which key 12 is provided.

In the front portion of the metal case 14 is mounted an ordinary twenty-four hour clock movement 17, of a small type, Fig. 3. An extended winding stem 11 is provided, upon which cylindrical disk 10 is secured in a suitable manner. Cylindrical disk is preferably made of brass and is provided 90 with slot 23, slot 23 extending through diameter or center of same from circumference to circumference.

In the rear back portion of the metal casing 14 a bushing 3 is mounted and secured 95 in a suitable manner through aperture provided for same. Bushing 3 is preferably made of brass and provided with an extended flange 27 preferably so that same may be firmly and cheaply secured to case 14. 100 Through bushing 3 passes a small shaft upon which spring 18 of light tension is mounted. An ordinary clock winding key 2, is provided and secured to end of shaft 19, spring 18 being secured in position by means of 105 bushing 3 and winding key 2. Spring 18 tends to hold winding key 2 and shaft 19 in an outward position from casing 14.

Upon shaft 19 is mounted a metal coin receiver 4, being cylindrical in shape and provided with a slot 22, slot 22 being cut in a suitable manner to receive a coin of certain 5 denomination, preferably a dime.

Extending from the top wall of case 14 to the lower portion 24 a metal wall is secured and held in a suitable manner. Wall 16, Fig. 4, is provided with aperture 8 and 10 slot 9, aperture 8 being slightly larger in diameter than the slotted coin receiving cylinder 4, and slot 9 being slightly wider than slot 22 of coin receiving cylinder 4. Wall 16 is also provided with aperture 15, allowing 15 an opening for setting stem 20 which extends through bank from clock movement 17.

Secured to case 14 by means of a rivet is provided a light spring 7 preferably of light 20 clock spring steel. Spring 7 extends slightly below the extreme upper end of slot 9 of wall 16.

Case 14 is provided with a coin slot 5 through which coin 6 passes and is received 25 in slot 22 of the cylindrical portion 4. Cylindrical portion 4 containing coin 6 in slot 22 is moved forward on a horizontal plane passing through aperture 8 and slot 9 in wall 16, pushing spring 7, (which projects 30 slightly over upper end of slot 9) forward and permitting cylindrical portion 4 containing coin 6 in slot 22 and winding key 2 in a forward position indicated by dotted lines and numerals 2¹—19¹—6¹—22¹ and 4¹, 35 key 2 being moved or turned in a clockwise direction until coin engages slot 23 of circular disk 10, thus forming connection between winding key 2¹ and winding mechanism of clock movement 17. After winding 40 has been accomplished key 2¹ is released and returns to original position 2 by spring 19 which is placed in a state of compression when key 2 and portion 4 are moved to position 2¹, 6¹, and 4¹. On the return from position 45 6¹, 4¹ and 2¹ coin 6¹ is not permitted to pass back to position 6 owing to interference of spring 7 over slot 9, which forces coin 6¹ from slot 22¹. Aperture 8 being only slightly longer in diameter than cylindrical portion 4¹ and containing coin 6¹ will permit 50 only cylindrical portion to return to position 4, coin 6¹ striking sides of aperture 8 and is forced from slot 22¹.

It will be seen that it is impossible to return coin 6¹ through aperture 8 and slot 9 of wall 16 no matter at what angle the coin 6¹ is moved by clock-wise or counter-clock-wise movement of key 2¹.

Of course it will be obvious that other 60 openings, besides slot 5, may be provided in the savings bank compartment not affecting the winding mechanism and also an aperture for bills.

My invention may be made of any size and 65 constructed of any material deemed convenient, economical and suitable for a device of this character, and while I have illustrated and described a form of construction and arrangement of parts found desirable in materializing my invention, I wish to include in the application for Letters Patent 70 all mechanical equivalents and substitutes that may fairly be considered to come within the scope and purview of my invention as defined in the appended claims. 75

I claim:

1. In a combination, a base, a housing mounted thereon, a partition forming a deposit chamber, a coin tripping aperture and slot contained in same partition, means for locking and unlocking said deposit chamber, a twenty-four hour clock movement mounted in said housing, an extended winding shaft provided for said clock movement, a cylindrical shaped disk, a slot milled 80 through said disc, said disc being mounted on end of said extended winding shaft, a bushing mounted in back portion of said housing, a small shaft passing therethrough, a slotted cylinder being mounted on inner 85 end of said shaft, a spring being placed on outward end of shaft opposite outward end of said bushing, a winding key mounted upon said shaft holding said spring on said shaft, between said bushing and said winding key, said shaft being free to move in a horizontal plane, always remaining at rest in an outward position from said clock movement by the compressed state of said spring mounted between said key and bushing on 90 said shaft.

2. In a combination, a base, a housing mounted thereon, a partition forming a deposit chamber, said partition or wall containing an aperture, said aperture having a slot cut in the upper center edge of said aperture, a small spring projecting slightly over the extreme upper end of said slot cut in said aperture, said combination allowing a slotted cylindrical portion containing a coin therein to pass forward in one direction, on return, of said slotted cylindrical portion containing said coin, to former position, said coin being tripped by interference of said spring or said walls of apertures, allowing said slotted cylindrical portion to pass through said aperture to former position, minus said coin which drops into deposit chamber. 115

In witness whereof I have hereunto subscribed my name this 11th day of July, A. D. 1923.

MENEFEE R. CLEMENTS.

Witnesses:

HARRY E. DENNY,
J. CANWERT.
